PROPELLER BLADE CONSTRUCTION

Frank M. Le Compte, Chatham, N. J., assignor to
 Curtiss-Wright Corporation, a corporation of
 Delaware

Application March 31, 1950, Serial No. 153,255

2 Claims. (Cl. 170—159)

1

This invention relates to propeller blades for aircraft and to the manufacture thereof.

Hollow metallic propeller blades are well known in the art, and many techniques have been proposed and used in the manufacture of such blades. Manufacture of hollow steel blades presents a number of different and difficult fabricating problems which result from requirements of high precision in manufacture, and the perfection of manufacturing technique which is required to endow the blades with adequate strength concurrently with minimum weight. The thin leading and trailing edges of hollow steel blades have always presented a rather serious problem due to the high vibratory stresses which occur in the propeller blades, these edge portions of the blades being likely to develop cracks if the steel of which the blade is made, and any materials added thereto, are not of the highest quality and free from defects. A further requirement in propeller blades generally is resistance to abrasion and this resistance particularly at the leading edge of the blade is best met by using relatively hard steel materials.

The present invention proposes to fabricate a hollow steel propeller blade from a seamless steel tube and to so form the tube that the airfoil portion of the propeller blade will comprise separate steel camber and thrust plates joined at their edges by a strong rubber bond. The rubber provides high resistance to fatigue and if appropriately applied provides adequate strength in the propeller blade to make it an adequate structure to resist the various loads and vibrative stresses to which the blade is subject in operation. As one of the features of the invention, the rubber bond between the blade plates is so located that it will not interfere with the leading or trailing steel edges of the blade so that the latter can be depended upon to yield high abrasion resistance.

Objects of the invention will become apparent from the above brief description and from the following detailed description when taken in connection with the drawings in which similar reference characters represent similar parts and in which Fig. 1 is a plan view of a typical propeller blade according to the invention;

Fig. 2 is a perspective elevation looking toward the tip end of the propeller blade;

Fig. 3 is an enlarged typical cross-section of the blade taken on the line 3—3 of Fig. 1;

Fig. 4 is an end elevation of a typical form of seamless tube from which the propeller blade is fabricated;

2

Fig. 5 is an enlarged section through a portion of the tube showing a first stage in the manufacture of the blade;

Figs. 6, 7 and 8 are fragmentary sections of portions of the blade tube showing consecutive steps in the fabrication of a propeller blade; and

Fig. 9 is a cross-sectional view of a blade airfoil section showing an alternative structural arrangement of the parts thereof.

Fig. 1 designates generally a typical blade whose planiform is adapted for the manufacturing techniques of the invention. In this arrangement, 10 shows a cylindrical butt adapted for securing in a propeller hub, the butt including a flange 11 to enable retention of the blade in the hub. A so-called cuff ring is shown at 12 which is usually provided in the blade butt to enable thickening or upsetting of the butt end and further to provide means for securing a cuff on the propeller blade if such is desired. The butt blends into a blade shank portion 14 tapered in planiform and reversely tapered in edgewise form, blending the butt into the airfoil portion 15 of the propeller blade. The leading and trailing edges 16 and 17 respectively of the airfoil 15 are substantially straight and parallel and terminate at a blade tip portion 18 which may be flat as shown, or curved outwardly according to the desire of the blade designer.

According to this invention, the blade airfoil portion 15 comprises a camber plate 20 and a thrust plate 21, the two plates being joined together at the leading edge by a rubber filleting mass 22 and at the trailing edge by a rubber filleting mass 24, said masses 22 and 24 being exposed in part to the camber surface of the blade as at 26 and 28 whereat they form a portion of the airfoil section of the propeller blade, and isolate the thrust and camber plates from one another. The rubber provides a vibration absorber if there is relative vibration between the thrust and camber plates, and due to the high fatigue resistance of the rubber, possible plate failures adjacent the leading and trailing edges are prevented. If desired, a central rubber rib 30 may also be applied within the blade, joining the thrust and camber plates, or in very thin blades, it may be desirable to have the rubber solid throughout the interior of the blade airfoil section or part thereof.

According to this invention, the thrust plate of the blade forms the principal structural member and carries a thickened leading edge portion 32 and a thickened trailing edge portion 34 integral therewith, said leading and trailing edge portions being of parent material with the thrust

plate 21 and thus having high resistance to abrasion. These edges likewise stiffen the propeller blade giving it adequate torsional and bending rigidity.

A preferred mode of fabricating a blade of the type described will be given. A seamless steel tube such as 36 in Fig. 4 is machined or otherwise formed to provide thickened portions 38 and 40 on the exterior of the tube, the upper margins of these thickened portions terminating substantially on a diameter of the tube as noted. The shank and butt portions of the ultimate propeller blade may be formed in any desired manner from the tube itself, by extrusion techniques utilized in forming the tube, or by the attachment of a separate preformed member to the basic tube.

After formation of the tube arrangement shown in Fig. 4, the tube is placed in a forming press and flattened to the form shown in Fig. 5 wherein the thickened portions 38 and 40 are transferred to the inside of the tube and wherein the thin upper portion of the tube of Fig. 4 is flattened to fold sharply over the thickened portions 38 and 40, leaving the folded edges 42 and 44. In flattening the tube, it is preferable to do so in forming dies so that the rudimentary camber plate 20 and the rudimentary thrust plate 21 are given approximately the configuration which they will have in the ultimate propeller blade. After flattening, operations indicated in Fig. 6 are performed which include first slitting the edges of the camber member 20 as at 46, longitudinally, whereby the camber member is parted from the thrust member 21 throughout substantially the entire airfoil section of the propeller blade. Reference may briefly be made to Fig. 1 in which these slits are indicated at 46, later filled with rubber to provide the surfaces 26 and 28, the slits extending from the blade tip inwardly to the transition zone between the shank 14 and the blade airfoil section 15. After slitting as at 46, the folded edges 44 and 42 of the rudimentary blade are trimmed off as shown in Fig. 6 along the line such as 48, whereupon a camber plate portion 50 between the folded portion 44 and the slit 46 is lifted away. The rudimentary blade now comprises the butt 10, the shank 14 and two unattached rudimentary camber and thrust elements 20 and 21, the edges of which are in spaced relation as at 52.

After the slitting and trimming operations, the thickened portions 32 and 34 of the thrust plate are trimmed to the form shown in Fig. 7 whereby they conform to the desired edge profile of the ultimate propeller blade. Thereupon, the rudimentary propeller blade is placed between formed dies having recesses complementary to the desired final airfoil section of the propeller blade. Suitable mandrels are placed between the thrust and camber plates 20 and 21 in a manner such as that described and indicated in my copending patent application Serial No. 55,264, filed October 19, 1948 now Patent No. 2,581,193. Thereupon, rubber is injected under pressure into the leading and trailing edge cavities of the propeller blade and bonded to the elements thereof, resulting in an edge configuration as shown in Fig. 8 and also in Fig. 3. If desired, as heretofore noted, a central rubber rib (Fig. 3) may be injected at the same time as the rubber edge fillets 24 and 22 are injected, or the blade may be wholly filled if the design calls for such filling. The techniques for rubber injection and bonding described in said copending application may be used in the fabrication of the propeller blade herein dis-

closed, or any other appropriate techniques may be utilized.

After formation of the rubber bonding fillets within the airfoil portion of the propeller blade, the blade is removed from the forming dies and the mandrels are removed from within the propeller blade whereupon the blade is completed except for final polish and finishing operations and such other operations as may be required in the machining of the butt 10 and in balancing the blade. Preferably, the tip 18 of the propeller blade is provided with a rubber fillet 56 shown in Fig. 1, joining the thrust and camber plates 20 and 21 at the same time as rubber is injected to form the fillets 22 and 24 and the rib 30 if the latter is required.

In Fig. 9 an alternative arrangement is shown wherein the edges of the camber plate 20' are offset toward the thrust plate 21 so that the distance between the edges of the respective plates is reduced. For this arrangement, these offsets being shown at 58 and 60, bonding area between the thrust and camber plates may be increased and the rigidity may likewise be increased because of the lesser thickness of filleting rubber between the plates. If this offset arrangement is used, the rubber of the fillets 24 and 22 will extend over the exterior of the edges of the camber plate 20' as at 62 and 64 to provide a smooth continuation of the airfoil cross-section of the propeller blade.

The blade herein described and shown may incorporate other well known provisions for reinforcing and stiffening and alternative metallic ribs are disclosed in the drawings in dotted lines in Fig. 9. They may be incorporated in the propeller for stiffness and strength in a manner well known in the art.

Where the term "rubber" is used herein it is intended to comprehend natural, artificial, or synthetic rubber-like materials and also, various yieldable plastic materials akin to rubber in their physical qualities. Essentially, the rubber-like material appropriate for use in this invention is a solid substance having high fatigue resistance, and elasticity which is great compared to that of the parent metal, such as steel, used for the thrust and camber blade plates and for the other structural components of the propeller blade.

It will be noted in the blade of this invention that the principal centrifugal loading thereon is carried by parent steel material all the way from the blade tip to the blade butt.

Though but a single embodiment illustrating the invention has been illustrated and described, it is to be understood that the invention may be applied in various forms. Changes may be made in the arrangements shown without departing from the spirit or scope of the invention as will be apparent to those skilled in the art and reference should be made to the appended claims for a definition of the limits of the invention.

What is claimed is:

1. An aircraft propeller blade comprising a hollow shank portion and bifurcated flattened blade portions extending therefrom including a thrust member and a camber member, said thrust member having thickened leading and trailing edge portions defining the leading edge and trailing edge of the blade, and said camber member lying spaced from and within the margins of said thrust member, the camber member edges lying inboard of said thickened edge portions of the thrust member, masses of rubber along and within the leading and trailing edges of said blade,

said masses being bonded to said members at their inner faces, a portion of each rubber mass forming an exposed part of the blade camber surface between the edge of said camber member and the thickened portion of said thrust member inboard of the edge of the thrust member.

2. A hollow metal propeller blade assembly having at one end a hollow tapered shank portion and at the other end a bifurcated flattened, edge-separated thrust and camber members bonded to one another adjacent the leading and trailing blade edges by rubber forming a blade portion, one of said members extending chordwise beyond the bonding rubber to provide metallic leading and trailing blade portion edges, 15 said blade having a typical cross-section wherein the thrust member is thickened along each edge, the camber member is narrower than and spaced apart from said thrust member forming gaps between said members inwardly of the leading 20 edge and trailing edge, and wherein the bonding rubber fills said gap and forms part of the external airfoil profile of the blade portion, said rubber extending inwardly in a chordwise direc-

tion, between the members and being bonded thereto to provide the sole lateral edge joints therebetween in the flattened blade portion of the assembly.

FRANK M. LE COMPTÉ.
